UNITED STATES PATENT OFFICE.

AUGUST BOUCHERY, OF BROOKLYN, NEW YORK.

DOUCHE MEANS.

Application filed September 26, 1924. Serial No. 740,077.

This invention relates to means or douches for irrigating and cleansing wounds and diseased tracts or canals in bodies such as the uterus, the vaginal or genital passage, and the alimental canal, for the treatment of endometrial, cervical and vaginal diseases, to remove offensive discharges, secretions and deposits, and to supplement the healthy activity of the tissues, and it is the primary object of the invention to provide an improved apparatus for this purpose to effect a thorough irrigation and embrocation of the diseased part by the application or the injecting of a medicated liquid or lotion into and upon the diseased part and the withdrawing of the irrigating liquid with unhealthy secretions.

A further object of the invention relates to apparatus for this purpose embodying therein a receptacle or chamber for receiving the discharged irrigating liquid or lotion after it has been applied to and drawn off from the diseased part with any unhealthy secretions for the purpose of making a diagnosis of the same.

Another object of the invention relates to an improved constructed and arranged injecting and ejecting nozzle and the provision of means to prevent the escape of liquid when applied to a cavity in the body with the resultant wetting of the clothes of the one being treated or the one administering the treatment.

A still further object of the invention relates to an improved suction creating means for drawing off the irrigating liquid after it has been applied to the diseased part.

Other objects and advantages will hereinafter appear.

In the drawing accompanying and forming a part of this specification Figure 1 is an elevational view of an installation of my improved douche apparatus to show the manner of utilizing the same as a douche and as an irrigating means to draw off the medicated liquid or lotion after it has been applied to a diseased part and the collecting of the drained off liquid for the purpose of diagnosing the same.

Figure 2 is a longitudinal sectional view, on an enlarged scale, of my improved injecting and ejecting nozzle and showing the arrangement of a shield applied thereto to prevent the escape of the irrigating liquid when treating a diseased part in a cavity or canal in the body.

Figure 3 is a side elevation, partly in section, and on an enlarged scale, of my improved suction creating means; and

Figure 4 is a side elevation, partly in section, showing my improved nozzle connected directly to a liquid carrying receptacle.

Similar characters of reference designate like parts throughout the different views of the drawing.

In carrying out the invention there is provided a combined injecting and ejecting nozzle, comprising a pair of concentric chambers, the inner chamber consisting of a tube 5 having one end constituting the inlet end, enlarged as at 6, and the opposite end arranged with the usual fluted nozzle 7 having discharge outlet means in the form of an orifice or orifices 8. The inlet end has a coupling 9 releasably connected thereto, as by screw threads 10, for the connection of a hose or tubing 11 to connect the inner chamber or tube 5 with a source of supply of medicated liquid or lotion, in the present instance, shown as an irrigating bag 12', which in use is suspended at some elevation whereby the irrigating liquid flows through the inner chamber by gravity. The tube 5 is made of suitable material preferably vulcanite.

The other chamber is in the form of a casing or tube 12 preferably of glass whereby the same may be readily cleansed. This tube is of a diameter greater than the tube 5 to provide a space or an outer chamber 13 between the two tubes, the tube 12 preferably being of a diameter to lie contiguous to the enlarged inlet end 6 and flutes of the nozzle 7 in the inner tube 5. The tube 12 extends from the inlet end of tube 5 and adjacent to the end of the nozzle 7, but preferably terminates at a point within the nozzle orifices, the spaces between the flutes of the nozzle and open end of the tube 12 serving as inlet means to said outer chamber 13 for the entrance of liquid ejected from the nozzle orifices.

The opposite end of the tube 12 is closed by a perforated cap 14 of pliable and yielding material, such as rubber, said cap embracing the end of the tube 12 whereby said tube is mounted upon the inner tube 5 at the inlet end thereof by clamping said cap between the end of tube 5 and a laterally extending flange of the coupling 9, as at 15. The liquid ejected from the nozzle and subsequent to the irrigating of the diseased

part enters into the chamber 13 and is discharged or drawn off from said latter chamber through an outlet in a projection 16 extending laterally from the tube 12 adjacent to its mounting upon the tube 5, said tube projection 16 being arranged for the connection of a hose or tubing 17 thereto as shown in Figure 1.

In the use of the device as a douche with the person being treated in a reclining position, as in a bed, to irrigate the uterus and vaginal or the alimentary canal the discharged or drawn off liquids may be led to and collected in a suitable receptacle, such as a pan 18, by the tube 17 as shown in dotted lines at 17^a. In such use of the irrigating apparatus to prevent escape of the irrigating liquid from the passage or canal being treated a shield is provided which is adapted to snugly fit the wall of the outer chamber of the nozzle and readily adjust itself to the wall of the passage or canal. This shield comprises a member 19 of elastic material, such as rubber, substantially of frusto-conical shape with the wall diverging outwardly and rearwardly of the nozzle 7. It will be obvious that the nozzle may be inserted into the vaginal or alimentary canal to a variable extent and then the shield adjusted along the nozzle in contiguous relation to the wall of the canal.

To assure the drawing off of the irrigating liquid from the chamber 13 suction means is provided. This suction creating means consists of a device adapted to be applied to a water faucet and the flow of water from the faucet causing the air to be evacuated, or partially so, from the chamber of the casing 12 through the tube 17, and comprises a pair of co-axial chambers 21, 22 (Figure 3), the chamber 21 constituting a pressure chamber and the chamber 22 an air chamber and having less area than the chamber 21. The air chamber 22 has an outlet in an axial tubular projection 23 to which a flexible hose or tubing 24 is adapted to be coupled, and the chamber has an inlet through a tubular projection 25 extending laterally from the casing of the chamber and through which the tubing 17 is connected. The chamber 21 is arranged in an inverted cone shaped casing open at one end and having a perforated closure for said opening. To adapt the same to be readily attached in water tight connection with a faucet 26 (Figure 1) this closure consists of a metallic cap 27 having threaded connection with the casing of the chamber having an axial perforation with a disk 28 of flexible or yielding material, such as rubber, clamped between the perforated cap 27 and the chamber casing, as at 29, as the cap is threaded to the casing, said disk having an opening axially of the chamber of less cross sectional dimension than the opening in the cap for

engagement of the faucet. The disk is also arranged with a conical deflector 30 to direct the water entering the chamber from the faucet to an outlet in an axial tubular projection 31. The casing of the water chamber 70 extends into the air chamber 22, as shown in dotted lines at 32, with the outlet projection 31 extending adjacent to but spaced from the inlet to the projection 23 and being restricted relative to the outlet in said 75 latter projection. The stream of water entering the water chamber is of greater volume than the discharge of said liquid from the restricted outlet 31 with the result that the water in said chamber is placed under 80 pressure and forcibly discharged from the outlet of said chamber, said discharged stream as it passes through the gap or space between the outlet 31 and the inlet to the outlet 23 of chamber 22 induces a flow and exhaust of the air from the chamber 22, which creates a suction in the tube 17 and connects chamber 13.

To collect the drawn-off irrigating liquid for the purpose of diagnosing the same a receptacle 33, which may be a jar or bottle, is interposed in air tight connection in the tube 17. For this purpose the receptacle opening is provided with a removable stopper 34 of rubber having a pair of elbow tubes 35, 36, 95 preferably of glass, in communication with the receptacle through perforations in the stopper and having air tight connection therewith, a section of the tubing 17 connected to the outlet 16 of the casing 12 being 100 connected to one of said elbow tubes, as the tube 36, and the other section of said tubing 17 connected to the inlet 25 of the air chamber 105 of the suction creating device connected to the tube 35. The suction creating device 110 evacuates the air from the receptacle 33 and thereby from the chamber 13 drawing the liquid discharged from the tube 5 into and from the chamber 13. The tubes 35 and 36 extend only to a slight extent into the receptacle 33 and out of contact with any liquid which may be collected in said receptacle, the one tube extending into the receptacle to a slightly greater extent than the other, as shown, to prevent the drawing of the liquid 115 from the one tube into the other.

In Figure 4 I have shown a unitary structure of nozzle and irrigating liquid supply receptacle, this receptacle being in the form of a bulb 12' having an outlet in a projecting portion 37 to which the end of the nozzle tube 5 is connected by inserting the same therein. The tube 12 co-operating with the nozzle tube 5 to provide the chamber 13 is enlarged at one end and engaged over the 120 bulb projection 27. The device may be also arranged with the shield 19.

While the invention has been described as particularly adapted for the treatment of disease of the genital canal or vagina and 130

uterus it is also applicable for the treatment of other diseased cavities of the body, such as the ear and nose.

Having thus described my invention, I claim:

1. In a douche device, a liquid carrying collapsible bulb receptacle having an opening in a tubular portion, a discharge nozzle engaged in the receptacle opening and open 10 to the receptacle for discharge of liquid from the receptacle to the nozzle, and a tubular member mounted at one end upon the tubular portion of the receptacle in which the nozzle is engaged and serving to clamp the 15 nozzle in the receptacle outlet, said tubular member extending around the nozzle in spaced relation thereto to form a chamber between said member and nozzle with the outlet end of the nozzle extending slightly 20 beyond the open end of the tubular member and the space between the open end of the tubular member and nozzle serving as an inlet to the chamber, and said tubular member having an outlet in a nipple extending laterally adjacent the end of the tubular member 25 at which it is mounted upon the tubular outlet portion of the receptacle for the exhaust of liquid from the chamber between the nozzle and tubular member, and a flexible conical shield engaged upon the tubular member for adjustment longitudinally 30 thereon.

2. In a douche, the combination of a liquid carrying receptacle having a discharge nozzle

35 zle connected thereto, a casing extending and forming a chamber around the nozzle having an inlet thereto for liquid discharged from the nozzle exterior of the casing and an outlet from the casing chamber; suction means connected to the casing outlet, and a collecting chamber interposed in the connection of the suction creating means with the outlet of the casing chamber.

40 3. In a douche nozzle, a tube arranged with enlargements at opposite ends the one end being longitudinally fluted and having outlet perforations therein and the other end an axial inlet; a nipple releasably mounted in the inlet end of said tube; a second tube of an internal diameter substantially the 45 same as that of the enlarged ends of the first tube to be engaged upon said first tube and provide a chamber between the two tubes open at the fluted end of the first tube, said second tube being connected at the opposite 50 end to the first tube and of a length to extend from said connection to a point adjacent to and within the fluted perforated end of the first tube; and an outlet nipple arranged for the connection of a hose extending from the 55 second tube adjacent its connection with the first tube; and a conical shield mounted upon the second tube to have adjustment along the same.

60 Signed at New York city in the county of New York and State of New York this 12th day of September, 1924.

AUGUST BOUCHERY.
